Primary Examiner — Susan E Krakower*Assistant Examiner* — Jerry Shiuan-Hua Hsu(74) *Attorney, Agent, or Firm* — Sven W Hanson(57) **CLAIM**

The ornamental design for a vehicle accelerator pedal extension, as shown and described.

DESCRIPTION

FIG. 1 is a perspective of a vehicle accelerator pedal extension illustrating my new design.

FIG. 2 is a front elevation view thereof.

FIG. 3 is a back elevation view thereof.

FIG. 4 is a right side view thereof.

FIG. 5 is a left side view thereof.

FIG. 6 is a top plan view thereof; and,

FIG. 7 is a bottom plan view thereof.

The broken lines illustrate portions of the vehicle accelerator pedal extension that form no part of the claimed design.
